UNITED STATES PATENT OFFICE.

GEORGE W. PEASE, OF PITTSFIELD, MASSACHUSETTS.

GARMENT.

Application filed March 18, 1921. Serial No. 453,429.

To all whom it may concern:

Be it known that I, GEORGE W. PEASE, a citizen of the United States, and a resident of Pittsfield, in the county of Berkshire and State of Massachusetts, have invented a new and useful Garment, of which the following is a specification.

The invention relates to apparel garments, and more particularly to knock-about or romper suits for children, and has for its objects to provide a suit which will be economical, which will have the advantages of a union suit in that it may be placed upon the person as an entirety, and in which the nether portion may be separated from the upper portion as with ordinary two piece suits.

A further object is to provide a suit of the character described which will be complete in itself, which will be provided with a sanitary drop flap, and in which strains and breakage due to movements of the wearer will be avoided or at least minimized.

These and further objects will more fully appear in the following specification and accompanying drawings considered together or separately.

One embodiment of the invention is illustrated in the accompanying drawings in which like parts in all of the several figures are designated by corresponding characters of reference, and in which—

Fig. 1 is a front view of garment embodying the invention, one side of the skirt of the jacket or blouse being raised.

Fig. 2 is a similar view of a portion of the garment showing both sides of the skirt raised.

Fig. 3 is a detail sectional view taken on the line 3—3 in Fig. 1.

Fig. 4 is a detail section of the trousers taken on the line 4—4 of Fig. 1.

Fig. 5 is a back view of the garment.

Fig. 6 is a section on the line 6—6 of Fig. 5.

Fig. 7 is a section of the trousers on the line 7—7 of Fig. 1, and

Fig. 8 is a detail view of a modified form of tab.

Fig. 9 shows a modified form of suspender.

Fig. 10 is a detail sectional view similar to Fig. 3 but showing a modified form of front fastening.

55 In the embodiment of the invention illustrated 1 designates a blouse or jacket which

preferably, although not necessarily, has a band 2 attached at or about the waist line to simulate a belt as in the well known "Norfolk" jacket. The blouse is open from the top to the bottom at the front and may be secured together by means of buttons 3 or other fastenings.

Secured to the inside of the front of the blouse and to one side of the vertical center thereof is a tab 4. The tab 4 is secured by its upper edge preferably about in line with the stitching at the lower edge of the band 2. The tab extends from a line below the center of the arm hole nearby to the center of the garment. The lower and side edges of the tab are free and unsecured to the blouse. The tab is provided with a plurality of buttonholes 5 as shown.

A similar tab 6 is secured to the inside of the blouse at the opposite side of the front opening therein. This tab 6 extends from a point below the armhole on that side of the blouse to a point a short distance beyond the vertical line of the front center of the blouse. The tab 6 is provided with a plurality of button holes 7 one of which 7^a is in alignment with the buttons 3 of the blouse when the latter is buttoned. The stitching at the lower edge of the belt will pass through the material of the coat and through the tabs 4 and 6.

A strap 8 is secured across the back of the blouse on the inside thereof a short distance above the waistline and parallel to the band 2. The strap 8 is preferably of the same material as that of the blouse and is stitched to the same at the ends only of the strap as shown at 9, that portion of the strap between the ends being free. Secured to the central unsecured portion of the strap is a depending tab or suspender 10 having a buttonhole 11 near its lower end.

In conjunction with the blouse above described is employed a nether portion consisting of a pair of knickerbockers 12, or trousers, as the case may be. The knickers are provided with a slit at each side. The slits extend from the waistband downward to the point 13 thus forming a sanitary drop seat 14. At each side, and in the slit, the drop seat is provided with a fold 16 which carries a button 15 adapted to engage a buttonhole in the front portion of the knickers.

The knickers are provided with the usual fly front the upper button of which is adapted to pass through a buttonhole at the

waistband of the knickers and not be covered by the fly. The said upper button will, therefore, be exposed as is common. The buttonhole 7^a is adapted to engage over the said button between the overlapping portions of the waistband of the knickers. The waistband of the knickers carries buttons 17 and 18 for engagement with the buttonholes in the tabs 4 and 6, and the back 10 drop carries a button 19 for engagement with the buttonhole in the tab or suspender 10. In addition the back drop may, if desired carry buttons 20. The buttons 17, 18 and 20 may be so located that the usual 15 suspenders may be applied to them when the knickers are worn without the blouse, or by means of such buttons the knickers may be secured to the usual shirtwaist.

The garment will have the appearance of 20 a two piece suit and, when the blouse and fly fastenings are disconnected, may be donned or removed as a union suit. When the suit is to be removed the front of the blouse and the fly are unbuttoned from the 25 neck to the crotch, as in the usual one piece suit and, as the buttonhole 7^a still engages the upper fly button the right side to the blouse will still be secured to the right side of the knickers while the left side of the 30 blouse is still secured to the left side of the knickers. The garment is therefore, as far as the wearer is concerned, a union suit and possesses all of the advantages of such 35 while possessing none of the disadvantages of that type of garment.

The blouse will not become soiled or worn as quickly as will the knickers and the latter may be laundered or repaired independently of the blouse, or a new pair may be 40 applied to the blouse when the first pair is discarded, thereby at least doubling the life of the blouse as compared to that of the upper portion of a true union suit.

The attachment of the back drop to the 45 suspender 10 will permit of the wearer bending over without causing undue strain on the button, as when the wearer bends the unattached portion of the strap 8 will be pulled downward and the ends thereof will 50 be drawn toward each other thus lengthening the distance between the top of the back drop and points of attachment of the band with the blouse.

While the invention is illustrated as applied to a boy's play suit, it is to be understood that the same may be carried out in connection with other garments and particularly with pajamas.

It is to be understood that instead of buttons and buttonholes the tabs and knickers may be provided with hooks and eyes, or any other suitable fastening means.

Instead of stitching the tabs 4 and 6, and the strap 8 to the coat, those members may be removably secured in place so as to be remov-

able from the garment, as shown in Fig. 8.

When the tabs 4 and 6 are buttoned or otherwise secured to the trousers, the garment is as much a union suit as is any union suit having a back drop. The buttons 17 and 18, or other forms of fasteners such as snap fasteners similar to those used on gloves, which may be employed instead of the buttons, need not be disturbed except when the garment is to be separated for 75 washing, repairing or replacement of one of its members.

Instead of employing the strap 8 and the suspender 9, the buttons 20 may each be removably secured to a tab 21 stitched or otherwise secured to the inside of the back of the coat, one on each side of the vertical center line thereof, as shown in Fig. 9.

In Fig. 10 is shown a modification in which instead of the tab 6 extending to the fly opening, a separate tab 22 is secured to the coat in line with the buttons 3. This tab depends inside of the trousers and is fastened to them by the button 7^a and preferably by means of an additional button or other fastening 23 as shown.

Instead of securing the tabs to the back of the garment and to the belt, the lower edge of the belt may be secured to the garment below the stitching which secures the tab in place, whereby said stitching will be concealed.

What is claimed is:—

1. An article of the character described, comprising a blouse portion and a trousers portion, a depending element secured by one edge thereof to the inside of the blouse portion at approximately the waist line, means for detachably securing the trousers to the element, the blouse being open from the neck to the bottom edge thereof, the trousers having a fly opening in alinement with the blouse opening whereby when the portions are attached one to the other there will be an opening from neck to crotch, one end of said element extending into the fly opening, and means for removably securing the said end in position in the front center line of the garment.

2. An article of the character described, comprising a blouse portion adapted to be opened at the front from the neck to the bottom thereof and a trousers portion having a fly opening, a series of horizontally spaced elements each stitched along one edge thereof to the inside of the blouse and depending therefrom at approximately the waist line, a belt stitched to the outside of the blouse at approximately the waist line, there being detachable means for securing the trousers to the elements on opposite sides of the front center line of the garment whereby the garment as a whole will be open from neck to crotch, one of said elements extending into the fly opening and

being detachably secured to the waistband of the trousers in said fly opening and be concealed by the outer fly flap.

3. An article of the character described, 5 comprising a blouse having a belt secured thereto, an element stitched to the inside of the blouse at each side of front opening therein, the upper edges of the elements being stitched to the material of the blouse 10 and to the belt, the lower edges of the elements being free, there being buttonholes in the elements, a member attached to the inside of the back of the blouse above the line of the belt, said member being attached 15 to the blouse at its ends only the central part of the member being free of the blouse, a suspender secured to the free portion of the member, there being a buttonhole near the free extremity of the suspender, the button- 20 holes of the elements and suspender being in approximate alinement.

4. An article of the character described comprising a blouse portion and a trousers portion, the blouse having a belt secured thereto, an element stitched to the inside of 25 the blouse at each side of the front opening therein, the upper edges of the elements being stitched to the material of the blouse and to the belt, the lower edges of the elements being free, there being buttonholes in 30 the elements, buttons on the trousers corresponding to the buttonholes in the elements, one end of one of said elements having a buttonhole for engagement with a button in the fly opening of the trousers. 35

This specification signed and witnessed this 17th day of March, 1921.
